United States Patent Office.

WILLIAM H. ELLIOT, OF NEW YORK, N. Y., ASSIGNOR TO JOHN KINGDON,
OF WASHINGTON, DISTRICT OF COLUMBIA.

Letters Patent No. 64,003, dated April 23, 1867.

IMPROVEMENT IN HAY-LOADER.

The Schedule referred to in these Letters Patent and making part of the same.

TO ALL WHOM IT MAY CONCERN:

Be it known that I, WILLIAM H. ELLIOT, of the City, county, and State of New York, have invented a new and improved Hay-Loader; and I do hereby declare that the following is a full and exact description thereof, reference being had to the accompanying drawings, and to the letters of reference marked thereon.

Similar letters of reference indicate the same devices in all the figures.

To enable others skilled in the arts to comprehend, make, and use my invention, I will proceed to describe its nature, construction, and operation.

The nature of my invention consists in the employment of certain devices for lengthening and shortening the cord between the end of the crane and the fork of an Elliot hay-loader, so as to reach the hay at a greater distance from the hay-rack than can otherwise be done.

Figure 1 is an elevation of the upper portion of an Elliot hay-loader, showing the head of the arm in section, fork *p* being a part of the same figure.

Figure 2 is a plan of the end of the arm, with the connecting-rod, arm, and pawl removed.

Figure 3 is an elevation of the arm and pawl.

a, standards of the crane which stands upon the hay-rack; *a'*, ratchet upon the top of the standard; *b*, spindle upon which the arm turns in the standard; *c*, head of the arm which supports the devices for adjusting the cord; *d*, wooden connection between the spindle and head of the arm; *e*, bolt which locks the arm in any required position; *f*, pulley which winds up adjustable cord *l*; *i*, pulley around which cord *k'* is wound when adjustable cord *l* is drawn out; *g*, movable arm which supports pawl *h*; this arm is placed between the two pulleys and has a motion around the same centre; *k*, spring which winds up adjustable cord *l*; *m*, brace of the arm; *o*, notch on pulley *f*; *p*, fork; *e'*, spring which pushes bolt *e* out of the notches on ratchet *a'*, and by means of rod *n* holds arm *g* in a vertical position. Any weight thrown upon cord *l* turns the pulley *f* upon its axis, which carries with it pawl *h* and *g*, and rod *n*, drawing bolt *e* into the notches on ratchet *a'*, and by these means locks the arm. When cord *l* hangs in a vertical position, it allows pawl *h* to catch notch *o* on pulley *f*, which prevents it from being unwound while in this position, but when cord *l* is carried out to the position represented by dotted lines *o*, as it must be to reach hay at some distance from the cart, the pawl *h* (which always rests against the cord *l*) is carried out with the cord so as to release pulley *f*, which allows the cord to unwind to any required distance, but it is at once wound up again by the power of spring *k* as soon as set at liberty. Pulleys *i* and *f* are attached together, and arm *g* is supported upon a hub between them.

The operation of my improved hay-loader is as follows: As the pitcher proceeds towards a cock of hay for the purpose of pitching it upon the hay-rack, the arm of the crane swings around lightly in the same direction. If the cock of hay stand near the hay-rack, the fork is inserted into it; then by depressing the handle the whole weight of the hay is thrown upon cord *l*; this locks the arm of the crane in its position so that it cannot swing around, the cord being of sufficient length so that when the fork is brought to a horizontal position the hay is held up clear of the ground. Now, by pushing upon the fork the hay is caused to swing up to the top of the load with very little effort on the part of the pitcher. But it is not always possible to drive near enough to a cock of hay to reach it with the ordinary loader, and it is for the purpose of meeting such difficulties that I have invented my improved hay-loader. As the pitcher goes towards a more distant cock of hay, the arm first swings around in that direction, the lower end of the cord is then carried out, as shown by dotted lines *r*, which raises pawl *h*, and releases cord *l*, so that it runs off any required length; the fork is then inserted into the cock, which is drawn by means of the fork to a position near the hay-rack. As the hay is drawn near the rack, the spring *k*, acting upon pulleys *i* and *f*, causes the cord to be wound up again, when pawl *h* catches the pulley and fastens the cord; the hay is now raised to the top of the load as before described. In my improved hay-loader both bolt *e* and pawl *h* are operated by cord *l*, bolt *e* being operated by the weight on the cord, and pawl *h* by the position of the cord.

Having described my invention, what I desire to have secured to me by Letters Patent of the United States, is—

1. The employment of an adjustable cord *l*, between the arm of the crane and the fork *p*, substantially as herein shown.
2. The employment of pulleys *f* and *i*, in combination with spring *k* and cord *l*, for the purpose of taking up the latter after it has been drawn out, substantially as specified.
3. Connecting together pawl *h* and bolt *e*, so that any motion given to the former will move the latter, substantially as and for the purpose specified.
4. So combining pawl *h* and bolt *e* with cord *l*, that the latter shall operate the two former, substantially as set forth.
5. Pivoting pawl *h* to movable arm *g*, so that these devices may have a little motion around the centre of the pulleys, substantially as herein shown.

WM. H. ELLIOT.
